UNITED STATES PATENT OFFICE.

EMIL TOBELE, OF DETROIT, MICHIGAN.

ROTARY VALVE.

1,256,395.

Specification of Letters Patent. Patented Feb. 12, 1918.

Application filed January 24, 1917. Serial No. 144,196.

To all whom it may concern:

Be it known that I, EMIL TOBELE, a subject of the Emperor of Germany, and resident of Detroit, in the county of Wayne 5 and State of Michigan, have invented certain new and useful Improvements in Rotary Valves, of which the following is a specification.

The present invention has reference, generally, to internal combustion engine valves; 10 and, the invention relates, more particularly, to an improved cooling means therefor.

The invention has for its principal object to provide cooling means for internal combustion engine valves, whereby, the same will be prevented from overheating due to the constant subjection of the same to the explosions occurring within the combustion chambers of the engine cylinders, 20 and the passage of the heated exhaust gases therethrough into the exhaust manifold.

It is also an object of my invention to provide novel means for inducing and circulating the valve cooling medium therethrough in a manner as will insure the proper functioning of the said valve at all times.

All of the foregoing together with additional advantageous details and arrangements of parts of the preferred embodiment of my invention will appear from the specific description hereinafter contained, when read in connection with the accompanying drawings forming a part thereof, wherein said embodiments of the invention is illustrated for the purpose of facilitating a full understanding of the present improvements.

40 In the drawings:

Figure 1 is a horizontal section through my improved valve;

Fig. 2 is a side elevation of the same;

Fig. 3 is a fragmentary vertical section 45 taken through the valve and valve chamber showing the mounting of the same; and

Fig. 4 is a fragmentary horizontal section through the valve chamber of a cylinder showing the positioning of the valve 50 therein, parts of the valve being broken away and shown in section.

Similar characters of reference are employed in all of the above described views to indicate corresponding parts.

55 Referring now more specifically to the several figures of the said drawings there

is provided a hollow rotatable cylindrical valve indicated in its entirety by the numeral 1, the valve being seated for rotation within a suitable valve chamber as formed 60 within the cylinder head 2 the said chamber being indicated by the numeral 3. As will be noted, an intake port 4 is formed within the cylinder head and has interposed therein a portion of the intake valve 1, the 65 valve being provided with a plurality of ports 5, whereby, the same may be used for timing the passage of the combustible gases to a multiple cylinder engine, the port, as will, be appreciated, intermittently aligning 70 with the various intake ports and as a consequence, permitting the proper intaking of the combustion charge into the combustion chamber of the engine. An exhaust port, not shown, is formed within the opposite side of the cylinder head 2 and has interposed therein an exhaust valve 1, the adjacent port as formed 75 therein being adapted to align with the exhaust port at predetermined intervals whereby to efficiently discharge the spent or exhaust gases into the exhaust manifold of the engine.

As is usual in the construction of internal combustion engines, there is arranged about the cylinders of the same a water jacket 7, 85 suitable openings being formed within the jacket, whereby the ingress and egress of the cooling medium will be permitted. Obviously, by providing the water circulating jacket 7, the cylinders of the engine 90 will be prevented from overheating, due to the constant explosion of the gases within the same.

With a view toward providing means whereby the hollow cylindrical valve 1 will 95 be sufficiently cooled, there is engaged with the outer face of the cylinder at a point adjacent one end of the valve chamber 3 a cap 8, which member may be secured in position through the medium of bolts or other similar fastening devices which are passed through the flange 9 as formed upon the said cap. An axial opening is formed within the cap 8 and receives therethrough a water supply pipe 10, which pipe extends approximately throughout the length of the said valve and is secured in position with relation to the same by means of a stuffing gland 11, the stuffing gland in turn, being engaged with an internally screw threaded extension 105 12 formed upon the outer portion of the cap 8. The outer end of the supply pipe 10 may

be engaged with any suitable source of supply, whereby water or other cooling medium may be furnished thereto and if desired, may be capped into the water circulating 5 jacket 7 as arranged about the engine cylinders. A discharge port 13 is formed within the cap 8 and communicates with the interior of the cylindrical valve 1, whereby, when the water as discharged thereinto from 10 the supply pipe 10 has been circulated therethrough, the same will be then taken off by way of the said discharge 13 and returned to its source of supply for cooling. In this connection, it is to be also appreciated, that 15 if I so desire, I may cap the discharge end of the said port 13 into the water circulating jacket 7 of the engine cylinder or if not, may extend the same together with the supply for the pipe 10 into engagement with the 20 usual cooling radiator as commonly employed upon motor driven vehicles.

In order that the valve 1 will be properly supported within the chamber or chambers 3 therefor, one extremity of the same is internally screw threaded as at 14 and is adapted to have turned into engagement therewith a complementally threaded plug 15, the said plug carrying thereupon a bearing spindle 16 adapted for reception within 25 a suitable bearing formed within one side wall of the cylinder head 2. Suitable gearing, not shown, is arranged upon the outer extremity of the bearing spindle 16 and is adapted to be connected with the crank shaft 30 of the engine, whereby, the valve will be properly rotated to permit the accurate timing of the same.

The marginal edge of the remaining end 40 of the cylindrical valve 1 is widened as at 17 and has formed therein an annular groove 18, which groove is adapted to receive an annular projection 19 as formed upon an annular cap 20, which cap is slidably received upon the outer faces of oppositely 45 disposed annular walls 21 formed integral with the cap 8 and projecting laterally therefrom. Expansible coiled springs 22 are received between the annular cap 20 and the annular walls 21 of the cap 8. Thus, by 50 reason of the fixed engagement of the cap 28

with relation to the valve chamber 3 of the engine, the annular cap 20 will be forced outwardly by reason of the coiled springs 22, causing the projection 19 to be snugly seated within the groove 18 arranged in the 55 marginal edge of the thickened portion 17 of the said valve 1. By such engagement, the fluid tight connection between the annular cap 22 and the valve 1 is provided and as a consequence, the water or other cooling 60 medium as being circulated through the valve 1 will be prevented from leaking onto the valve chamber or the cylinders of the engine.

Although I have in the above description, 65 specifically referred to my improved valve as being of the rotatable type, it will be understood, that the improvements are not limited to this particular form of valve, but may be applied to any form of hollow cylindrical valve in which, it is desirable to provide means for cooling or maintaining the 70 same at an even temperature.

As hereinbefore indicated, I do not wish to be understood as confining the invention 75 to the particular embodiment chosen for illustration herein, nor to the exact construction and arrangement and adaption of the parts shown and described, but I reserve the right to make any changes and alterations that fairly fall within the spirit and scope of the invention.

I claim:

In a hollow cylindrical engine valve, a supply pipe; a cap for receiving and supporting said supply pipe having a discharge opening therein and laterally projecting annular flanges formed upon one face thereof, a cap having an annular projection engaged with said annular flanges of the first mentioned cap, springs interposed between said first and second mentioned caps for normally forcing the latter outwardly, the adjacent ends of the hollow cylindrical valve being grooved to receive the annular projection 95 arranged upon the second mentioned cap, as and for the purpose set forth.

In testimony whereof, I affix my signature hereto.

EMIL TOBELEER.
